UNITED STATES PATENT OFFICE.

PERCY M. GRIFFIN, OF ALBANY, NEW YORK, ASSIGNOR TO CONSOLIDATED CAR-HEATING COMPANY, OF ALBANY, NEW YORK, A CORPORATION OF WEST VIRGINIA.

DRIVING GEAR FOR DOOR MOTORS.

Application filed April 12, 1922. Serial No. 551,952.

To all whom it may concern:

Be it known that I, Percy M. Griffin, a citizen of the United States, residing at Albany, in the county of Albany and State 5 of New York, have invented certain new and useful Improvements in Driving Gear for Door Motors, the following being a full, clear, and exact disclosure of the one form of my invention which I at present deem 10 preferable.

For a detailed description of the present form of my invention, reference may be had to the following specification and to the accompanying drawing, wherein

15 Fig. 1 is a section view of my device;

Figs. 2 and 3 are details.

My invention relates to a transmission or power-conveying agency to be interposed between a door-motor and the door operated 20 thereby for the purpose of providing a yielding drive that will cause the stoppage or reversal of the motor in the event of the door being blocked or obstructed. This transmission is in the nature of a differential, planetary gearing in which the driving pressure reacts yieldingly upon a stationary abutment, in the event of said pressure exceeding a predetermined limit, and thereby 25 operates the necessary means for stopping or reversing the engine.

Referring to the drawing, 1 indicates the driving motor, which is here shown as an electric motor, although the principle of my invention may also be embodied in connection 35 with a pneumatic or other fluid-pressure type of engine, in which case, the initial reduction gearing may be omitted. The shaft of motor 1 is coupled to the primary shaft 3 in bearings 4 by means of a coupling 2.

40 The shaft 3 drives worm-wheel 6 by means of a screw 5 and a pinion 9 is fast on shaft 7 of said wheel 6, this shaft 7 being journaled in the housing by bearings 8. The pinion 9 drives a gear-wheel 10 which carries as the floating member of a planetary

45 gearing a bevelled pinion 15 on a projection 14 in which the stud-shaft 16 of the pinion is journaled. Wheel 10 has a hollow shaft 11, in bearings 12, with a radial arm 42 thereon to operate the limit-switches 40 and

50 41 at the end of each run of the door. Through hollow shaft 11 passes loosely a shaft 13 which acts to control the floating member and carries on hub 35 a radial arm 55 36, that, during the door-closing movement,

bears against a yielding stop or abutment formed by spring 37 which, in turn, rests against screw-plug 38 in the wall of the housing. Movable with the arm 36 is a switch-operating arm 36^a, the functions of 60 which will be later described. A fixed stop 37^a engaged by arm 36 prevents its rotation in the opposite direction. On the outer end of shaft 13 aforesaid is a bevelled gear-wheel 17 engaging said pinion 15, while in 65 line with 17 is a similar wheel 18 (on shaft 19 in bearings 20) which also engages pinion 15. On said shaft 19 is secured a radial arm 32 which at each end of its arc of travel strikes one or the other of the pneumatic 70 buffers 33 and 34. On the outer end of shaft 19 is a toothed clutch-member 21 which normally engages a similar member 22 that slides on and rotates with the hub of a bracket 24, which is normally supported and 75 guided by an extension 23 of shaft 19. Said bracket 24 carries the usual door-operating arm 25. A spring 31 normally presses clutch member 22 into engagement with member 21. A lever 28, pivoted at 29, has fingers 80 extending into a groove in member 22 for working the clutch manually and also has a cam-lever 30 mounted thereon at 27 and provided with a handle 26. By moving this handle 26 in the direction of the arrow, the 85 cam lever 30 is forced against the wall of the housing and thereby moves lever 28, against the force of spring 31 aforesaid, to disengage the clutch. When the clutch is disengaged the door may be moved by hand, but when 90 the lever is engaged, wherever the door may stand, the clutch members will snap back into engagement whenever their teeth come into the right position after the starting up 95 of the engine.

The operation of the above described gearing will be evident. The motor will rotate wheel 10, and, since the wheel 17 is held against rotation (by the spring stop on the door-closing movement and by the fixed stop 100 on the door-opening movement) the pinion 15 will rotate, as it travels around 17, and thereby compel wheel 18 to rotate and operate the door through the agency of shaft 19, clutch-members 21, 22, bracket 24 and arm 105 25. The driving pressure also reacts on wheel 17 and, if the pressure is acting to close the door, and if, because of the door being blocked or obstructed, the pressure exceeds a predetermined value or magnitude, 110

then the spring stop or abutment 37 will yield and allow a slight rotation of shaft 13 together with arm 36 and hub 35. As appears in Fig. 2, that will also rotate a second arm 36^a on hub 35, which will operate an electric switch 39 to either stop or reverse the motor. If it is to merely stop the motor, the switch 39 will be in the main motor circuit, while if it is to reverse it, the switch will be in the circuit of a magnet acting on the engine reverser. I prefer the former allowing spring 37 to reverse the motor mechanically until its circuit is reclosed and the same action repeated until the obstruction is removed.

What I claim as new and desire to secure by Letters Patent is:

1. The combination with a rotatable shaft provided with a door motor of a door-operating transmission including a member reacting against a normally stationary yieldable abutment, and a controlling device for the motor operated by said member.

2. The combination with a door motor of a door-operating transmission including a rotatable shaft provided with a member reacting under the door-closing pressure against a normally stationary yieldable abutment, and a controlling device for the motor operated thereby.

3. The combination with a door motor of a door operating transmission including a normally stationary yieldable abutment, a motor-driven member acting on the door and having means engaging said abutment, and a controller for the motor operated thereby.

4. The combination with a door motor of a door-operating transmission including a motor-driven shaft, gearing between said shaft and the motor, a normally stationary yieldable abutment, gearing between said shaft and said abutment, and a motor controller operated by the yielding of the abutment.

5. The combination with a door motor of a door-operating transmission including a motor-driven shaft provided with a rigid abutment, a gearing operated thereby, a yieldable abutment normally engaging said shaft abutment, said gearing exerting pres-

sure against the door and reactionary pressure against said abutment, and a controller for the motor operated by the abutment pressure.

6. A transmission adapted to be interposed between a door and its operating motor comprising a differential, planetary gearing having its floating member controlled by a yielding abutment, a door-operating arm, and a motor-controlling switch operated by the yielding of said abutment.

7. A door motor transmission comprising a door-operating member provided with a yieldable member operable when power applied thereto exceeds a predetermined value, a motor controlling switch operated by said yieldable member, and a manual clutch for disconnecting the door-operating member.

8. A door motor transmission gear comprising a reversible rotary motor moving synchronously with the door, and a yieldable stop cooperating with said member to neutralize its door closing movement when said movement is resisted by an abnormal force.

9. A door-motor transmission comprising rotary reduction gearing, an oscillating door-operating arm, a motor-controller operated by excess pressure on the door, a housing for the mechanism, and a disconnecting-clutch accessible from without the housing.

10. A door-motor transmission comprising a screw and worm-wheel, a planetary gear driven thereby, a motor-controlling switch operated by the back-pressure on the door, an oscillating door-operating arm, and a clutch for disconnecting the door.

11. A door motor transmission comprising a rotary member, a door operating arm driven thereby, a yieldable stop cooperating with said member to neutralize its door closing movement when said movement is resisted by an abnormal force, and limit switches operated by the rotary member at each end of the door movement.

Signed at Albany, county of Albany, and State of New York, this 3rd day of April, 1922.

PERCY M. GRIFFIN.
